UNITED STATES PATENT OFFICE.

JOHN M. MURPHY, OF NEW YORK, N. Y., ASSIGNOR OF TWO-THIRDS TO JULIUS MARTIN, OF SAME PLACE, AND FRANK H. BEECHER, OF SEYMOUR, CONNECTICUT.

DESIGN FOR A BADGE.

SPECIFICATION forming part of Design No. 18,194, dated March 20, 1888.

Application filed October 11, 1887. Serial No. 252,074. Term of patent 14 years.

To all whom it may concern:

Be it known that I, JOHN M. MURPHY, of the city, county, and State of New York, have invented a new and original Design for a 5 Badge, of which the following is a full, clear, and exact specification.

My invention relates to a new design for a badge; and the leading feature of my design consists in the representation of a fireman's hat.

Reference is to be had to the accompanying drawing, forming a part of this specification, in which the figure of the drawing is a perspective view of my newly-designed badge.

In carrying out the design the body consists 15 of a substantial oval figure, A, the sides of which are provided with a regular inward curl or curve, A'. From the lower or reduced end of said figure, which represents the cape of a hat, double lines B are projected outward 20 to a central point, which lines, at their base or inner ends, are connected by a curve-line, B', imparting the effect of a ribbed conical offset, B'', solid with the body and representing the crown of a hat. From the lower side of the 25 conical figure B'', near the outer end, a wavy-line, b, is projected, which line b intersects with an inwardly-inclined line, b', terminating in the oval figure A. The lines b and b', in connection with the conical figure B'', constitute a figure, 30 C, and represent a frontispiece.

Upon the surface of the oval figure A, at the upper or enlarged end, a group of figures, d, d', d'', and d''', are crossed one upon the other, representing, respectively, the ladder, hook, 35 pick, and trumpet usually employed by firemen.

The combined figures A, B', and C represent a fireman's hat.

Upon a rectangular figure, D, having a ribbon-like surface and extending above the enlarged or upper end of the figure A, the representation of the American spread-eagle is produced, as shown at D', and a circular figure, E, representing a ring, is arranged to have the appearance of interlocking the eagle 45 figure and aforesaid figure A.

In the complete design the image of an eagle appears as secured upon a variegated ribbon holding in suspension a fireman's hat.

I claim—

The design for a badge herein shown and described, the same consisting of the oval figure A, having upwardly-curved side lines, A', the conical figure B'', formed of converging double lines B, the figure C, formed of the lines 55 b and b', the crossed figures d, d', d'', and d''', produced upon the figure A, respectively representing a ladder, hook, pick, and trumpet, the rectangular figure D, representing a ribbon, the figure D', produced upon the ribbon-like surface, representing an eagle, and a circular figure, E, interlocking the figures A and D', whereby an eagle is represented upon a ribbon background supporting a fireman's hat, as set forth.

JOHN M. MURPHY.
